J. McADAMS.
LINE PRINTING MACHINE.

No. 403,206.

Patented May 14, 1889.

UNITED STATES PATENT OFFICE.

JOHN MCADAMS, OF BROOKLYN, NEW YORK.

LINE-PRINTING MACHINE.

SPECIFICATION forming part of Letters Patent No. 403,206, dated May 14, 1889.

Application filed September 20, 1887. Serial No. 250,170. (No model.)

To all whom it may concern:

Be it known that I, JOHN MCADAMS, of Brooklyn, in the county of Kings and State of New York, have invented a new and useful Improvement in Line-Printing Machines, of which the following is a specification.

I will describe in detail a line-printing machine embodying my improvement, and then point out the novel features in claims.

10 In the accompanying drawings, Figure 1 is a side view of the portion of a machine embodying my invention which includes the printing and supporting rollers and also the inking mechanism. Fig. 2 is a plan of the 15 parts shown in Fig. 1. Fig. 3 is a plan of a portion of an ink-fountain made according to my invention; and Fig. 4 is a transverse section thereof upon about the plane of the line xx , Fig. 3. Fig. 5 is a section lengthwise of 20 the machine of the parts shown in Fig. 1. Fig. 6 is a section, lengthwise of the machine, of an arrangement of tapes or cords and brushes whereby the paper may be cleaned as it passes to the line-printing rollers; and 25 Fig. 7 illustrates another arrangement of tapes and cords, including a beater and an air-blast apparatus, whereby the paper may be similarly cleaned.

Similar letters of reference designate corresponding parts in all the figures.

A designates the main frame of the machine, and B B' designate the pairs of line printing and supporting rollers by which the lines are printed upon opposite sides of the 35 sheet.

C designates the feeding apron or cords, which pass over suitable supporting-rollers, C' C², and by which sheets of paper are fed from the feeding end of the machine to the 40 printing or ruling apparatus; and C³ designates a portion of the delivery apron or cords on which the paper is delivered from the machine.

In Fig. 6, which represents the feeding end 45 of the machine, I have shown brush-rollers or dusting-rollers D D', and two systems of endless cords or tapes, a b, which pass around and are suitably directed by rollers a' a² a³ a⁴ b' b² b³ b⁴, so as to carry the paper in contact with the brushing or dusting rollers D D', as represented by the arrows in Fig. 6. The dusting roller or brush D has extending

below it a suitable shield, b⁵, which prevents the dust and scraps from falling on the paper as it is fed along by the apron or cords C. The 55 paper is by hand fed to the cylinder or roller a' and the tapes or cords a, and is carried around in the direction indicated by the arrows, and by which one side is presented to the action of the brush D, and then passes on 60 the roller or tapes and cords b' b, by which its other side is presented to the action of the brush D'. From the tapes or cords b the sheet is delivered to the apron or cords C, and is by them carried forward in the direction 65 indicated by the arrows in Fig. 6, to the apparatus for printing or ruling the lines thereon.

In Fig. 7 I have shown a dusting apparatus of another form which embodies my invention. In this apparatus the paper is fed between two series of cords or tapes, D² D³, which are carried and moved by rollers D⁴ in the directions indicated by the arrows. Below the upper paper-carrying portions of the tapes 70 or cords D³ is a roller or beater, D⁵, of polygonal form, or having projections, and which is so arranged that its corners or projections will strike against and lift the paper and tapes or cords, and by such beating action 75 any dust or dirt will be detached from the under surface of the paper and fall into the dust-pan D⁶.

To clean the upper surface of the paper, I employ a blast of air, which may be supplied 85 from a blower, as shown, through a pipe, D⁶. The paper passes from the feeding apron or tapes C directly between the cylinders or rollers B B' of the first pair and B' B of the second pair, and is delivered onto the apron or 90 cords C³, which convey it from the machine. In passing between the first pair of rollers B B' the upper surface of the paper is printed by the roller B, and in passing between the rollers of the second pair its lower surface is 95 printed with lines by the roller B. Each of the four rollers B B' has a series of disks, c, the edges of which are presented in a straight line from end to end of the roller, and which are set at a distance apart equal to the desired 100 distance between the lines. The disks of the rollers of each pair are so placed that the disks of the roller B, for example, come between the disks of the roller B', and consequently

when the paper is passed between these two rollers the natural elasticity of the paper holds it against the edges of the printing-disks *c*.

The four rollers *B B' B' B* are intended to 5 be interchangeable, so that they may be used in any arrangement or combination, and the disks of the several rollers may be set at various distances apart to produce lines on the paper at any desired distance apart.

10 In order to provide for readily changing the rollers *B B'*, so as to form different combinations of them, their journals *d* are supported in slotted bearings *d'* in the frame *A*, as best shown in Fig. 1, and they are provided

15 at opposite ends with friction-wheels *e*, which bear one on another. The friction-wheels *e* of the lower rollers of the two pairs bear upon corresponding friction-wheels, *E²*, which are upon a shaft, *E*, extending across the machine 20 beneath the aforesaid rollers, and to which motion may be imparted by a driving-belt passing over a pulley, *E'*.

The friction-wheels *e*, which are upon opposite ends of the rollers *B B'*, are of such diameter that when the wheels at opposite ends of the upper and lower rollers of each pair are in contact the edges of the disks *c* of one roller will be in proper relation to those of the other roller to perform the printing operation, 30 and by the frictional contact of the wheels *E²* *e* the rollers of each pair are driven from the shaft *E*. It will therefore be seen that when the rollers are placed in any combination their friction-wheels *e* will be in contact with 35 each other, and the wheels *e* upon the lower rollers will be in contact with the frictional driving-wheels *E²*.

40 *F F* designate the ink or color fountains, from which the upper roller *B* of the first pair and the lower roller *B* of the second pair are supplied with ink or color.

45 *G G* designate the two color-rollers, which rotate in the fountains, and the journals of which are supported in slotted bearings *f* and by anti-friction wheels *f'*. I have also represented other ink or color wheels or rollers, *G'*, which rotate in contact with the lower roller *B'* of the first pair and the upper roller *B'* of the second pair. These inking or color wheels or 50 rollers *G'* are supplied with color by suitable feeders, *g*, from fountains *G²*, secured upon the frame of the machine. The ink or color rollers *G'* may be arranged to ink or color certain of the disks of the supporting-rollers *B'*, 55 so as to produce on the paper head or other lines in a different color, as is indicated by the arrangement of the rollers *G'* in Fig. 2.

60 Instead of employing a separate fountain for the ink or color rollers *G'*, which are arranged to supply ink or color to only one or two of the disks which are on those rollers which serve as supporting-rollers *B'*, I may form a divided fountain, such as I have represented in Figs. 3 and 4. In those figures *F* 65 designates the main portion of the fountain, wherein the color-rollers *G* are intended to turn, and the fountain is constructed with

transverse partitions *h h' h²*, thereby forming compartments *F' F²*. The fountain also has beyond the partitions *h' h²* a supply box or 70 compartment, *F³*, which is in full communication with the compartment *F'* by a bridge or covered passage, *h³*, extending through the compartment *F²*. The portion *F⁴* of the compartment is in free communication with the 75 main portion *F* by means of the bridge or covered passage *h⁴*, which extends across the compartment *F'*, and color which is supplied to the main portion *F* and compartment *F⁴* overflows across the bridge *h³* and fills the 80 compartment *F²*.

85 From the above description it will be understood that the same color or ink will fill the compartments or portions *F F² F⁴*, while a different color or tint may be used in the compartments *F' F³*, which are in free communication by the bridge or covered passage *h³*. By means of this divided fountain color wheels or rollers may be arranged to supply one or more of the printing-disks at the end 90 of the printing-rollers with ink of a different color or tint from that supplied to the main portion of the ink-fountain and delivered by the roller *G* along the length of the printing-roller.

95 In Fig. 2 I have represented the upper printing-roller *B* as having at its end an arrangement of printing-disks, *c*, whereby it operates, in connection with the disks at the end of the upper supporting-roller *B'*, to produce head-lines, and the color-roller *G*, for supplying the upper printing-roller *B*, has color-disks *G³ G³*, which run in and take color from the compartments *F' F²* of a color-fountain like that shown in Figs. 3 and 4. In 105 order to render the ink-fountains *F* and the ink-rollers *G* self-adjusting relatively to the printing-rollers *B B'*, I have represented them as supported upon inclined seats or rests *a* 110 upon the frame. They will then have a tendency to gravitate downward, which will carry them in a direction to cause the rollers *G* to come into contact with the disks or printing or pen rollers and to maintain them in such working-contact. I thus dispense with any 115 means of fastening the ink-fountains in place, and enable them and their rollers *G* to readily adjust themselves in proper position relatively to the printing-rollers.

120 For each inking-roller *G*, I employ a wiper, *H*, which may be made of india-rubber, and which is approximately tangential to the roller. This wiper serves to remove from the roller the surplus of ink. It is held in a suitable holder, *H'*, which is free to slide toward 125 and from the roller *G*, and to which are connected screws *i*, provided with nuts *i'*. By adjusting these nuts the holder *H'*, with its wiper *H*, may be made to lap more or less upon the roller *G*, as may be required to increase 130 or reduce the quantity of ink carried over by the roller. Springs *j*, as shown in Fig. 2, may be employed for adjusting the holder *H'* toward the roller *G*, while the screws and nuts

i i' may serve to withdraw the wiper from the roller.

What I claim as my invention, and desire to secure by Letters Patent, is—

- 5 1. The combination, in a line-printing machine, of pairs of rollers, those of each pair being arranged one above another and all provided with disks *c*, and which are interchangeably fitted in the machine, so that
- 10 either of each pair may serve as a printing-roller and its companion as a supporting-roller, and of inking apparatus for supplying color to the disks of the printing-rollers, substantially as herein described.
- 15 2. The combination, with pairs of line-printing and supporting rollers arranged side by side and those of each pair one above another, of friction-wheels applied to their journals and bearing one on another, and a driving-shaft having friction-wheels in contact with those upon the lower rollers of the pairs, whereby the rollers are driven and held out of contact and at the proper distance apart for printing, substantially as herein described.
- 20 25 3. The combination, with the printing-rollers and their opposite supporting-rollers, all supplied with disks *c*, of ink fountains and rollers for supplying color to the disks of the printing-rollers, and separate ink fountains and wheels or ink-rollers for supplying color to certain of the disks of the supporting-rollers, substantially as herein described.
- 30 4. In a line printing or ruling machine, the combination, with printing-rollers provided with series of disks for line-printing, of color-rollers and color or ink fountains arranged at an inclination toward the printing or pen rollers and made self-adjusting relatively thereto, substantially as herein described.
- 35 40 45 5. In a line printing or ruling machine, the combination, with the line printing or ruling devices, of tapes or cords, which carry the paper on its way to the said printing or ruling devices, and brushes or beaters past which the tapes or cords travel, and which serve to clean the paper while it is carried by the

tapes or cords, substantially as herein described.

6. In a line printing or ruling machine, the combination, with the printing or ruling devices, of pairs of tapes or cords between which the paper is carried on its way to said devices, a beater for knocking or beating the tapes or cords and paper to clean the under surface of the paper, and an air-blast pipe for cleaning the upper surface of the paper, substantially as herein described. 50

7. In a line-printing machine, the combination, with printing and supporting rollers and color wheels or rollers, of an ink or color fountain having compartments formed by transverse partitions, wherein wheels operate to deliver one or more colors upon certain of the printing-disks, and having the remaining portions in communication by a passage or 60 65 passages leading beneath the first said compartment or compartments, substantially as herein described.

8. The combination, in a line-printing machine, with a printing-roller and a supporting-roller, of an ink-fountain and an inking-roller turning therein for supplying the disks of the printing-roller, and a wiper of india-rubber, arranged approximately tangential to the inking-roller and operating thereon, substantially as herein described. 70 75

9. The combination, in a line-printing machine, with a printing-roller provided with printing-disks and the oppositely-arranged supporting-roller, of the ink-fountain and an inking-roller, a sliding holder carrying a wiper, which is arranged approximately tangential to the inking-roller, and which bears thereon, and devices whereby said holder is adjustable to vary the lap of the wiper on the 80 85 inking-roller, substantially as herein described.

JOHN MCADAMS.
